BALL WINDING MACHINE

Hiram N. Huse, Providence, R. I.

Application October 25, 1947, Serial No. 782,069

9 Claims. (Cl. 242—3)

1

This invention is directed to an improvement in ball winding machines wherein one or more threads are wound upon a core, and provides a construction wherein the ball, during the winding operation, is held between two driven rotatable heads.

These heads carry a plurality of driven rollers which engage the surface of the ball as it is being wound. Each roller is carried in a driven roller support.

This general construction is shown in my prior Patents 1,959,760 of May 22, 1934 and 2,076,565 of April 13, 1937, the present invention providing, however, an improved construction wherein means are provided for separating the movements of the rollers and the roller supports. This enables me to prevent excessive voids and thread crossings on the ball surface, and to produce a very hard, dense and truly spherical ball. These are very desirable features particularly when winding golf balls.

In the accompanying drawings wherein I have illustrated an embodiment of my invention.

Fig. 1 is a longitudinal sectional view of the rotatable heads of the machine;

Fig. 2 is a section through Fig. 1, taken on the line 2—2;

Fig. 3 is an elevational view of the right hand end of the machine of Fig. 1; and

Fig. 4 is an explanatory cam diagram.

Inasmuch as the ball being wound is held between two opposed rotating heads, some means must be provided for permitting the heads to be moved away from each other as the ball diameter increases. In the instant machine I may employ a construction for this purpose similar to that disclosed in my prior Patent 1,959,760 above referred to. For this reason I have omitted showing this construction in the drawings of the instant application.

Referring to the drawings in detail, 2 and 4 designate the two driven rotatable rotors or heads of my improved machine. These rotors or heads are opposed to each other as above mentioned and as illustrated in Fig. 1. Inasmuch as the rotors are identical in construction a description of rotor 2 which has been shown in section will suffice for both.

The main drive shaft is designated 6, this shaft driving both rotors or heads.

The rotor 2 is driven in a constant direction from the main drive shaft 6, through gears 8 and 10, tubular rotor drive shaft 12 and its flange 14 which is bolted to the rotor or head 2 as shown

2

at 16. Gear 10, it will be noted is keyed to the rotor drive shaft 12.

As just mentioned, the rotor drive shaft 12 is tubular, and extending centrally through this shaft and into the housing of the rotor or head 2 is a spindle drive shaft 18.

A tubular or quill shaft 20 also extends through the rotor drive shaft 12, and immediately surrounds the spindle drive shaft 18. This shaft 10 may properly be termed a cam shaft in that it mounts a cam 22 which is positioned within the housing of the rotor or head 2.

Reverting to the spindle drive shaft 18, it will be seen from the drawings, particularly Fig. 1, that a gear 24 is keyed to the inner end of this shaft. This is a spindle drive gear.

Each of the rotors, or heads 2 and 4 is equipped with three ball-supporting rollers 26 for supporting the ball 28 as it is being wound, each 20 roller preferably being provided with a cap 29 similar to the cushion caps 70 of my prior Patent 2,076,565. These caps, as explained in that patent are so constructed as to slip around on the surface of the ball-supporting rollers to turn and twist with the ball, and hence prevent abrasion of the ball surface. The winding thread is designated 30.

Each ball-supporting roller 26 is rotatable on its own axis. The gear 24, referred to as a spindle drive gear, meshes constantly with three pinions 32, rigidly secured to a spindle 34 with which each ball-supporting roller 26 of the head 2 is provided. Each of these spindles extends through a rotatable roller support 36 which is mounted in the forward or ball-winding end of the housing of the rotor or head 2, the projecting end of each spindle extending into a ball-supporting roller.

Each ball-supporting roller 26 is carried on a stub shaft 38 which is inclined to the axis of rotation of the rotors 2 and 4, this shaft being mounted in suitable bearings in the roller supports 36. Each of these stub shafts carries a bevel gear 40 constantly meshing with bevel gear 42 on each of the spindles 34.

It will be apparent from the description so far given that rotation of the spindle drive shaft 18 will effect simultaneous rotation of the ball-supporting rollers 26 of the head 2, the rollers all rotating in the same direction, through train composed of the gears 24, 32, spindles 34 and gears 42 and 40.

In addition to rotation of the ball-supporting rollers 26 on their individual axes, the supports 36 for these rollers (one for each ball-supporting

roller) are adapted to be rotated in parallel relation on their individual axes.

These roller supports are mounted in a spider 44 which is universally mounted on a ball and socket arrangement 45. This spider is provided with pintles 46 extending into eccentric rings 47 wherein the roller supports are mounted.

Mounted in the inner end of the spindle drive shaft 18 and projecting therefrom is a stub shaft 52 carrying a double faced gear 54. Each roller support is reduced in diameter at its rear end where it carries a gear 56. These three gears are in mesh with one part of the gear 54. The other part of gear 54 meshes with a gear segment 58. This gear segment is carried by a cam lever 60 fulcrumed on a pin 62 which is fixed with respect to the housing of the head or rotor 2. The cam lever carries a cam roller 61 which follows the cam track 64 of the cam 22.

It will be apparent from the immediately foregoing description that the roller supports 36 will be rocked about their individual axes by the gear segment or rack 58 depending upon the shape of the cam track 64 of the cam 22, from which the gear segment receives its motion.

In my previous Patent 2,076,565 the cam 12 corresponding to instant cam 22 was secured directly to a shaft 6 corresponding to the spindle drive shaft 18 of this application. In my improved construction the cam 22 being keyed instead to the cam shaft 20 is free to rotate relatively to spindle drive shaft 18.

I have already explained that the head 2 is driven from shaft 6 through gears 8 and 10, the latter in effect being keyed to the head.

On the outer end of the cam drive shaft 20 is a gear 66 which is keyed to the shaft and meshes with a gear 68 keyed to the drive shaft 6. As will be apparent from the drawings the gear ratio between gears 8 and 10 driving the head 2 is different from that between gears 68 and 66 driving the cam drive shaft 20, so that the head and the cam shaft rotate at different speeds.

The spindle drive shaft 18 which as mentioned is free to rotate within the tubular cam-drive shaft 20 carries a pinion 70 at its outer end meshing with a gear segment 72 keyed to fulcrum pin 74 mounted in the gear 66, the latter being keyed to shaft 20. The fulcrum pin 74 is free to turn in gear 66 and projects beyond the inner face of this gear and rigidly secured thereto is cam lever arm 76 carrying cam follower roller 78 riding in cam track 80 of a cam 82 which is rigidly secured to the face of gear 10.

Operation

Inasmuch as the two heads 2 and 4 are identical in construction, it will be appreciated of course that the action taking place in one head is simultaneously being duplicated in the other head.

Let it be assumed that the main drive shaft 6 is rotating at a constant speed: Inasmuch as the head 2 is geared directly to this shaft through gears 8 and 10 it is obvious that the head will rotate constantly at a fixed speed.

The cam drive shaft 20 being keyed directly to gear 66 which is rotating at a different speed from head-driving gear 10, the cam-drive shaft will be rotated at a different speed from the head 2, and inasmuch as the cam 22 is keyed directly to shaft 20 the cam 22 necessarily rotates at a different speed from the head 2. It is apparent therefore that always there is relative rotary movement between head 2 and cam 22.

Inasmuch as the cam 22 rotates relatively to the head or housing 2, and inasmuch as the fulcrum pin 62 for the cam lever 60 is fixed with relation to the head or housing 2, as above pointed out, it will be apparent that the cam lever 60 may be pivoted on its fulcrum pin 62. As will be seen from the diagram, Fig. 4, the cam 22 is shaped to provide two dwells 84 and 86 and two active surfaces 88 and 90, arranged alternately. Consequently throughout traverse of the cam follower along the dwell 84 the cam-lever 60 remains stationary, and the roller supports 36 remain stationary so far as rotation on their individual axes is concerned merely being carried about the axis of the machine by the head. The cam follower next engages an active segment 88 of the cam causing the cam lever to rock thereby to rotate the roller supports 36 in parallel relation on their individual axes all in the one direction. A dwell 86 of the cam 22 is next encountered so that the roller supports again remain stationary so far as rotation about their individual axes are concerned. Next the active segment 90 of the cam is encountered and the cam lever 60 is again rocked, but in the reverse direction to its original motion again to impart rotation to the roller supports in parallel relation about their individual axes. This constitutes a cycle, and it will be apparent that during each cycle the roller supports are rotated about their individual axes in parallel relation, first in one direction and then in the other, with an appreciable dwell between reversals.

Up to this point it will be seen that the head 2 and cam 22 rotate constantly in one direction, the cam rotating at a different speed from the head, thereby through the mechanism described intermittently effecting rotation of the roller supports in parallel relation on their individual axes, first in one direction and then in the other, with an appreciable dwell between reversals as determined by the dwells on the cam.

As above pointed out rotation of the shaft 18 effects rotation of the ball-supporting rollers 26 about their individual axes which are inclined to the longitudinal axis of the machine, power being transmitted from the shaft 18 through gears 24 and 32, spindles 34, gears 42 and 48.

The function of the cam 82 and its associated elements is to cause the spindle drive shaft 18 and hence the spindles 34 and the ball-supporting and driving rollers 26 to rotate about their individual axes in a constant direction during the periods the roller supports are "dwelling," the ball-supporting rollers deviating from this common or constant direction due to the action of the cam lever 76 and its cam follower roller in the cam, whereby the rollers 26 become fixed in relation to the roller supports 36 during rotation of the roller supports in either direction in parallel relation about their individual axes.

Normally the ball-supporting and driving rollers 26 turn in one common direction, due to the differential movement of the gears 10 and 66. The only departure from this action is when the roller supports are rotated in parallel relation about their individual axes to alter or vary the setting of the rollers relatively to the head. Consequently the cam 82 is so shaped that whenever the roller supports 36 are rotated in either direction in parallel relation about their individual axes the rollers 26 rotate with the supports, the rollers at all other times rotating in a constant direction.

Again referring to the diagram of Fig. 4, during the period represented by line A—B the rollers 26 are rotating in relation to the supports 36. The supports during that period are not rotating on their individual axes but are merely being carried around with the head 2 about the axis of rotation of the head; during the period represented by the line B—C both the rollers and the roller supports are rotating in fixed relation; during the period represented by C—D the rollers are rotating on their individual axes in relation to the roller supports which throughout that period are not rotating on their individual axes; while during the period represented by line D—A the rollers and roller supports are rotating in fixed relation.

In other words means are provided for effecting a deviation in the normal rotation of the rollers 26 to cause them to move integrally with the roller supports whenever the roller supports are rotated in parallel relation on their individual axes in either direction.

It will be apparent from all of the foregoing, that if the thread 30 were led to a core 28 from a fixed source in line with the vertical plane through the core center, and the rollers 26 simply carried around with the heads 2 and 4, the core would merely be rotated about the longitudinal axis of the machine, and the thread would simply be wound about the core equator. It is evident also that were the axes of the driving rollers 26 parallel to the axis of rotation of the core the core would be given the same motion. The axes of the driving rollers, however, are inclined to the longitudinal axis of the machine, so that with the heads stationary and the driving rollers rotating the core would be turned or rotated about an axis which is at the same angle to the longitudinal axis of the machine as the roller spindles 38.

However, rotation of the rotors 2 and 4 about the longitudinal axis of the machine and rotation of the rollers 26 on their individual axes which are at an angle to the longitudinal axis of the machine, take place simultaneously. In addition the roller supports 36 are rotated periodically in parallel relation on their individual axes, first in one direction and then the other, with an appreciable dwell between rotations, and at such times because of the cam 82 and its associated mechanism there is no relative movement between the rollers and the roller supports. In other words, the rollers 26 deviate from their normal rotation so as to move integrally with the roller supports whenever the roller supports are rotated in either direction in parallel relation about their individual axes.

It will be apparent therefore that as the thread 30 is drawn onto the core a true sphere is produced by intermittently changing the driving axis of the core relative to the winding axis. It will be appreciated also that by the provision of the cam 82 and its coaction with the cam 22 I eliminate the compound movements of the rollers 26 and roller support 36. The separation of the movements of the rollers and roller supports effects a flatter and more dense thread winding on the ball, and prevents the closed weave or thread crossings at a single point on the ball surface which are produced by the mechanisms of my two prior patents above referred to.

It is to be understood that changes may be made in the details of construction and arrangement of parts above described within the purview of my invention.

What I claim is:

1. In a ball winding machine, the combination of opposed rotatable winding heads, ball-driving rollers carried by said heads, means for normally rotating said rollers on their individual axes in a common direction, supports for said rollers carried by said heads, means for intermittently rotating said supports first in one direction and then in the opposite direction in parallel relation on their individual axes, and means for intermittently deviating the normal rotation of the ball-driving rollers to cause the rollers to rotate integrally with the roller supports during rotation of the latter in either direction.
- 5 2. In a ball winding machine, the combination of opposed rotatable winding heads, ball-driving rollers carried by said heads, means for normally rotating said rollers in a common direction about individual axes which are angularly disposed with respect to the axis of rotation of the heads, supports for said rollers carried by said heads, means for intermittently rotating said supports first in one direction and then in the opposite direction in parallel relation on their individual axes, and means for intermittently deviating the normal rotation of the ball-driving rollers in timed relation with rotation of the roller supports to cause the rollers to rotate integrally with the supports during rotation of the supports.
- 10 3. In a ball winding machine, the combination of opposed winding heads, means for rotating the same on a common axis, ball-driving rollers carried by said heads, means for normally rotating said rollers in a common direction about individual axes which are angularly disposed with respect to the axis of rotation of the heads, supports for said rollers carried by said heads, means for intermittently rotating said supports simultaneously first in one direction and then in the opposite direction in parallel relation on their individual axes which are parallel to the axis of rotation of the heads, and means for intermittently deviating the normal rotation of the ball-driving rollers in timed relation with the intermittent rotation of the roller supports to cause the rollers to rotate integrally with the supports during rotation of the supports.
- 15 4. In a ball winding machine, the combination of opposed winding heads, means for rotating the same on a common axis, ball-driving rollers carried by said heads, means for normally rotating said rollers in a common direction about individual axes angularly disposed with respect to the axis of rotation of the heads, supports for said rollers carried by said heads, cam controlled means for intermittently effecting rotation of said supports simultaneously first in one direction and then in the opposite direction in parallel relation on their individual axes, and cam controlled means for interrupting the normal rotation of the rollers in timed relation to rotation of the roller supports whereby the rollers rotate integrally with the supports during rotation of the supports.
- 20 5. In a ball winding machine, the combination of opposed winding heads, means for rotating the same on a common axis, ball driving rollers carried by said heads, means for normally rotating said rollers in constant rolling contact with the ball in a constant direction about individual axes angularly disposed with respect to the axis of rotation of the heads, supports for said rollers carried by said heads, cam actuated means for intermittently effecting rotation of said supports simultaneously first in one direction and then in the opposite direction in parallel relation on their

individual axes, and cam actuated means for effecting deviation of the said rollers from their normal rotation in timed relation to rotation of the roller supports whereby the rollers and supports rotate integrally.

6. In a ball winding machine the combination of opposed winding heads, means for rotating said heads as a unit about a common axis, sets of ball-supporting and driving rollers carried by each head, a stub shaft for mounting each roller the said shafts being set at an acute angle to the axis of rotation of said heads, spindles for normally rotating said shafts in a constant direction with the rollers in constant rolling contact with the ball, mounts for said spindles, cam mechanisms for intermittently effecting rotation of said mounts in parallel relation about their individual axes first in one direction and then in the opposite direction, and cam mechanism operable during rotation of the said mounts to effect integral rotation of the mounts and rollers.

7. In a ball winding machine the combination of opposed winding heads, means for rotating said heads as a unit about a common axis, sets of ball-supporting and driving rollers carried by each head, spindles for driving said rollers, said spindles operating normally to rotate said rollers in a constant direction in rolling and driving contact with the ball, a mount for each spindle, means for intermittently effecting rotation of said mounts in parallel relation about axes parallel to the axis of rotation of the heads, first in one direction and then in the opposite direction, and cam mechanism operable momentarily to effect a deviation in the normal rotation of said spindles whereby the spindles and mounts will be rotated integrally.

8. In a ball winding machine the combination of a winding head, a gear for rotating the same in a constant direction, roller supports mounted in said head, ball-driving rollers carried by the roller supports, a cam rigidly affixed to said gear, a second gear cooperating with said cam for normally effecting rotation of said rollers in a constant direction, a second cam, said second cam being mounted in and rotatable relatively to said head, said second cam being operative periodically to effect rotation of said supports in parallel relation first in one direction and then the other, and means cooperating with the first mentioned cam and the said second gear whereby the rollers are caused to deviate from their normal rotation so as to rotate integrally with the roller supports.
9. In a ball winding machine the combination of a winding head, a gear for rotating same in a constant direction, a plurality of roller supports rotatably mounted in said head, a ball-driving roller rotatably carried by each of said supports, a second gear concentric with the first gear but rotating at a different speed therefrom, a cam in said head driven by the second gear whereby the cam will be rotated relatively to the head, a driving connection between the last mentioned cam and the roller supports whereby the roller supports will be rotated periodically in parallel relation first in one direction and then in the opposite direction, and a second cam carried by the first mentioned gear and connected to the second gear by a cam lever and operatively connected to said rollers, whereby during rotation of the roller supports the supports and rollers will rotate as a unit.
